UNITED STATES PATENT OFFICE.

OTTO C. ROHDE, OF TOLEDO, OHIO, ASSIGNOR TO CHAMPION SPARK PLUG COMPANY, OF
TOLEDO, OHIO, A CORPORATION OF DELAWARE.

DESIGN FOR A SPARK-PLUG CORE.

54,128.

Specification for Design.

Patented Nov. 4, 1919.

Application filed June 2, 1919. Serial No. 301,357. Term of patent 14 years.

To all whom it may concern:

Be it known that I, OTTO C. ROHDE, a citizen of the United States, residing in Toledo, in the county of Lucas and State of Ohio, have invented a new, original, and ornamental Design for a Spark-Plug Core, of which the following is a specification, reference being had to the accompanying drawing, forming a part thereof.

The figure is a side elevation of a spark plug core showing my new design.

The marked feature of my design resides in the corrugated form of the upper end portion of the core, which is the exposed portion of the core when used in a spark plug.

I claim:

The ornamental design for a spark plug core, substantially as shown and described.

OTTO C. ROHDE.
